John W. Dow

UNITED STATES PATENT OFFICE.

HIRAM LUCAS PIPER, OF MONTREAL, QUEBEC, CANADA.

GOLF-TEE-FORMING MOLD.

Application filed February 21, 1924. Serial No. 694,283.

To all whom it may concern:

Be it known that I, HIRAM LUCAS PIPER, a subject of the King of Great Britain, and resident of the city of Montreal, Province of Quebec, Dominion of Canada, have invented certain new and useful Improvements in Golf-Tee-Forming Molds, and do hereby declare that the following is a full, clear, and exact description of same.

10 In the game of golf it has been found that the forming by hand of the small mound or tee upon which the ball is poised for driving results in certain objectionable features such as waste of the sand or like material from 15 which the tee is formed, variance in the height of the tee for instance, to the detriment of consistency in play and furthermore lacks the speed and facility of formation calculated to avoid time wasting, congestion of succeeding players to the driving tees. Accordingly my invention appertains to a hand mold by means of which a 20 player can remove the minimum amount of sand from the supply and without wastefulness, convey it to the driving location and with speed and facility deposit it in a stand-ardized molded mound ready to support the ball.

25 In the use of such an article to mold a golf tee and deposit it in position it is of extreme importance that the molds be capable of being readily free from the molded tee as otherwise in removing the mold disintegration of the tee may result. It is therefore an object of my invention to provide a 30 mold for forming golf tees and which by its construction ensures, in the freeing action, an effective relative movement around the molded tee whereby sticking of the mold 35 with resultant disintegration of the tee, is avoided.

40 Another object is to provide a golf tee forming mold which in freeing itself from the molded tee, exerts a shearing action upon the tee to positively free the mold.

45 The above with further objects and advantages will be hereinafter more fully described and particularly pointed out in the appended claims.

50 For full comprehension, however, of my invention reference should be had to the accompanying drawings forming a part of this specification, in which the same refer-

ence characters indicate the same parts and wherein:

55 Fig. 1 is a side elevation of the mold;

Fig. 2 is a plan view thereof; and

Fig. 3 is a bottom plan.

Fig. 4 is a cross-section on line 4—4 Fig. 2.

60 As disclosed by the drawings, the mold consists of a frusto-conical or other preferred contoured matrix of suitable height, the walls 2 of which are free at the top and bottom edges, the top of the matrix being closed by a disc-like cap 3 attached by a narrow strip 4 to the top edge, the remainder of the top edge and cap being free and permitting of relative movement therebetween.

65 The wall 2 of the matrix is separated from the bottom at one side, the matrix being composed of a springy sheet metal or other suitable elastic material lending the capability of compression to the matrix to move the free ends of the walls together to contract the matrix and upon release to spring 70 back to the original expanded position, the free relation between the cap and walls permitting of this manipulation. For convenience in handling the matrix each separated 75 end portion of the wall carries a wing 5 whereby the matrix can be grasped by a player, inserted base downwardly into sand, contracted to compress its sand content and while still contracted carried to the driving position where release of the compression 80 causes the matrix to expand so that it can be removed to expose a symmetrical stand-ardized mound or tee, the wings being of approximately the same vertical extent as the 85 mold to minimize the compass of the article and facilitate packaging thereof. In the molding of the tee the cap 3 forms a flat top which if desired may be centrally indented to steady the ball, by forming a boss 6 upon the underside of the cap 3. This cap 3 is pref-90

95 erably of greater diameter than the top opening of the matrix so that the cap overlaps the top edge and in the contracting action the latter slides freely beneath the cap without possibility of being obstructed thereby 100 the free side of the cap being maintained in intimate association with the top edge of the matrix by a retaining member in the form of a finger overhanging the cap and in slidable relation thereto to permit relative movement 105 of cap and wall while restraining upward

displacement of the cap under the molding pressure. The finger 9 may be constituted by any overhanging portion of the matrix walls, a preferred form being that shown by the 5 drawings and composed of a flat piece clipped to the wall and bent into gooseneck form to present a slot within which the edge of the cap is located.

As shown particularly in Fig. 3 the separated ends of the wall 2 overlap in the form of a helix so that in the contracting action the ends of the wall of the matrix telescope, this telescoping inaugurating a shearing action upon the molded sand within the 15 matrix, the edge 6^a of the inner end of the wall in its movement around the interior positively shearing the sand from the matrix to facilitate release, this action being augmented by an additional shearing edge disposed around the interior of the mold and 20 relatively movable thereto, this additional shearing edge 7 being projected from edge 6^a in advance of the latter in the helical path thereof to combine therewith in presenting 25 spaced shearing edges functioning at separate points about the mold to adequately free the molded content. As shown this additional shearing element is presented preferably by means of a strip 7 continuing from 30 the lower portion of edge 6^a adjacent the lower edge of wall 2, and bent upwardly, parallel with the wall to present the end 8, which being of strip form presents a front 35 shearing edge effective in one direction and a rear shearing edge effective in the opposite direction, the contraction and release of the matrix effecting the movement in opposite directions. The strip 7 is in the form of a 40 resilient wire whereby a tight contact of the end 8 with the interior of the wall 2 is maintained and the upper edge of this strip between edges 6^a and 8 constitutes a ledge or shoulder lending sufficient support to the 45 molded content of the matrix as to prevent likelihood of premature dropping of the tee from the matrix should the wall 2 be inadvertently slightly released in being carried to the driving location. The helical construction of the matrix enables the wall 50 2 to span the gap which would otherwise exist between the ends of the wall and therefore presents a completely encircling wall preventing lateral escape of sand or the like during the molding operation and 55 ensuring a most efficient self supporting density in the molded tee.

As shown in the drawings the inner coil portion of the matrix is constituted preferably by a separate flap portion fixed to one 60 end to the outer contractile wall portion by fastener 8^a bent outwardly through slots 10 in the inner and outer wall portion.

A golf tee mold constructed as above described will enable a tee to be molded from sand or the like in a quick and facile man-

ner, without waste of sand and freely deposited without likelihood of disintegration due to sticking of the sand in the mold.

What I claim is as follows:

1. A mold for making golf tees from sand and the like, comprising a contractile and expandable matrix, the ends of the wall of the matrix overlapping and having relative movement during the contraction and 75 expansion of the matrix.

2. A mold for making golf tees from sand or the like, comprising a matrix, a shearing element upon the interior wall of the matrix and means for moving the shearing element round the matrix to free the matrix 80 content.

3. A mold for making golf tees from sand and the like, comprising a matrix of frustoconical form with a contractile wall, means whereby the wall is contracted to compress the sand content and an interior ledge disposed adjacent the larger end of the matrix and having an upholding action upon the sand content. 85

4. A mold for making golf tees from sand and the like, comprising a matrix, spaced shearing elements upon the interior wall of the matrix and means for moving the shearing elements round the matrix to free the matrix content. 90

5. A mold for making golf tees from sand and the like, comprising a matrix, a shearing element upon the interior wall of the matrix and presenting opposed shearing edges 100 and means for moving the shearing element in opposite directions round the matrix to free the matrix content.

6. A mold for making golf tees from sand and the like comprising a matrix with a contractile wall of helical form, the inner edge 105 of the helix constituting a shearing edge for freeing the matrix content, and an additional shearing element carried by the inner end of the helix in advance of the inner edge thereof. 110

7. A mold for making golf tees from sand and the like comprising a matrix with a contractile wall of helical form, and a strip continuing from the inner end of the helix 115 interiorly of the matrix and terminating in an angularly disposed end substantially parallel with the adjacent wall of the matrix.

8. A mold for making golf tees from sand and the like comprising a matrix, the wall of which is contractile to compress sand within the matrix and presents an opening at one side to accommodate the contraction and a flap spanning said opening. 120

9. A mold for making golf tees from sand and the like, comprising an open-ended matrix with a contractile wall and a cap for the top of the matrix, connected at one side to the matrix and having its major portion 125 free of the matrix and a finger carried by the 130

matrix and extending over the cap in slid-
able relation thereto to restrain upward
movement of the cap relatively to the ma-
trix.

5 10. A mold for making golf tees from sand
and the like, comprising a contractible and
expansible matrix of sheet material in
helical form, the inner edge of the helix
being exposed to the interior of the matrix
10 and movable within the latter during the
contraction and expansion thereof.

11. A mold for making golf tees from sand
and the like, comprising a frusto-conical
matrix open at the bottom and including a
15 wall of sheet material and of double ply for
a portion of its circumference, the inner ply
being in movable relation to the outer ply.

12. A mold for making golf tees from sand
and the like, comprising a matrix of frusto-
20 conical form with a wall of spring material,
having its top and bottom edges free and
being separated from top to bottom at one
side, one end of the wall continuing inter-
riorly of the other end to span the opening
25 presented by the separation, an outwardly
extending wing upon each separated end

wall portion, a cap over the smaller end of
the matrix and a narrow connecting strip
between the cap and the top edge of the
matrix.

13. A mold for making golf tees from sand
and the like, comprising a matrix of frusto-
conical form with a wall of spring material,
having its top and bottom edges free and
being separated from top to bottom at one 35
side, one end of the wall continuing inter-
iorly of the other to span the opening pre-
sented by the separation, a resilient wire ex-
tending from the inner end of the wall near
the bottom edge and terminating in an up-
turned end substantially parallel to the wall,
an outwardly extending wing upon each 40
separated end wall portion, a cap overlap-
ping the smaller end of the matrix, a narrow
connecting strip between the cap and the 45
top edge of the matrix and a finger carried
by the wall and extending over the top of
the cap in slidable relation thereto.

In testimony whereof, I have signed my
name to this specification.

HIRAM LUCAS PIPER.
